LOUIS P. JUVET, OF GLENS FALLS, NEW YORK.

DESIGN FOR A BRACELET.

SPECIFICATION forming part of Design No. 18,189, dated March 20, 1888.

Application filed January 19, 1888. Serial No. 261,333. Term of patent 7 years.

To all whom it may concern:

Be it known that I, LOUIS P. JUVET, of Glens Falls, in the county of Warren and State of New York, have invented a new and original Design for a Chain Bracelet, of which the following is a specification.

Reference is to be had to the accompanying drawing, which represents a view in perspective of my newly-designed chain bracelet.

The leading feature of the design consists in a bracelet-chain and an ornament in the form of a padlock decorated on its face with fancy figures.

A is the chain of the bracelet, and B the attached ornament or fastening, in the form of a padlock decorated on its face with the fanciful design.

I claim—

The design for a chain bracelet herein shown and described, the same consisting of a bracelet-chain and an ornament in the form of a padlock decorated on its face with fancy figures.

LOUIS P. JUVET.
